UNITED STATES PATENT OFFICE.

ADOLPH BALLEMBERG, OF NEW YORK, N. Y.

COMBINED CORNER-PLATE AND SPRING-SUPPORT FOR BEDS.

1,271,116.

Specification of Letters Patent.

Patented July 2, 1918.

Application filed June 16, 1917. Serial No. 175,112.

To all whom it may concern:

Be it known that I, ADOLPH BALLEMBERG, a citizen of the United States, and a resident of the city, county, and State of New York, have invented a new and useful Improvement in Combined Corner-Plates and Spring-Supports for Beds, of which the following is a specification.

This invention has relation to a means for detachably uniting the sides and ends of a bed or a like article of furniture or a box, trunk or any article of this general character and the object of this invention is to provide a device of this character which will detachably unite the parts of the bed or the like at the corners or the junctures of the ends and sides, and which will afford a rigid, secure and firm joint at this point.

A further object of my invention is to provide, in conjunction with the corner joint above referred to, a suitable support for a bed spring or the like.

With these, and other objects to be herein-after disclosed, in view, I have devised the combination of parts to be hereinafter set forth and particularly pointed out in the claims appended hereto.

For a more particular description of my invention, reference is to be had to the accompanying drawing, forming a part hereof, in which,

Figure 1 is a side elevation of my device in use, parts being broken away to disclose its construction,

Fig. 2 is a plan view of the same,

Fig. 3 is a front elevation of the corner plate and spring support,

Fig. 4 is a sectional view on the line 4—4 of Fig. 3, looking in the direction of the arrows,

Fig. 5 is a perspective view of one of the locking lugs, and

Fig. 6 is a face view of one of the plates which interengage with the corner plate.

Throughout the various views of the drawings, similar reference characters designate similar parts.

In the preferred embodiment of my invention, as disclosed in the accompanying drawing, I have shown and will refer to my improved corner plate as used in conjunction with a bed, although it is clearly obvious that the same is readily adaptable for use in connection with various articles.

In the drawing, 1 indicates one of the side members of the bed or other article to which

the device is applied. Secured to this member 1 at its end is a plate 2, which plate is preferably embedded in the member 1 with its front face flush with the inner face of the member 1. The plate 2 is secured to the side member by means of the screws 3, or other suitable securing devices, and projecting from the outer face of the plate are locking lugs 4. These lugs 4 are in the form of downwardly turned hooks and are wedge shaped in vertical cross section.

Secured to the end 5 of the bed in like manner as by the screws 8 is a plate 6, which plate is substantially like the plate 2 and is provided with lugs 7 which are substantially like the lugs 4 in configuration and cross section except that they are oppositely disposed or in the form of upturned hooks.

The locking corner plate and spring support, which interlocks with the lugs 4 and 7 to unite the parts 1 and 5 together at right angles to one another, comprises an angular plate having vertically extending sides 9 and 10 disposed at an angle to one another, and these sides are provided with apertures 11 and 12. The side 9 has the apertures 11 and these apertures are of a configuration to allow the lugs 4 to pass therethrough. The apertures 12 in the side 11 are likewise disposed and shaped to allow the lugs 7 to pass through them. It will therefore be noted that these apertures are oppositely disposed with respect to one another. Extending laterally from the lower ends of the angular sides 9 and 10 is a plate 13, and when the device is in position, as shown in Figs. 1 and 2 this plate 13 extends outwardly at an angle from the junction of the parts 1 and 5 of the bed, and acts as a rest or support for a corner of the bed spring or the like. As these plates are situated at the four corners of the bed, it will be seen that the spring will be firmly supported at its four corners.

From the foregoing, the operation of my improved device will be readily understood. To unite the parts, the side member 1 and end member 2 of the bed are placed at right angles to one another, as disclosed in Fig. 1, the lugs 4 are passed through the apertures 11 and the lugs 7 are passed through the apertures 12 and when the parts 1 and 2 are moved slightly in opposite directions, the lugs 4 and 7 are caused to move slightly in their respective apertures so that their ends overlap the ends of the apertures and lateral movement of the corner plate is pre-

vented. Furthermore, the inclined sides of the lugs 4 and 7 frictionally engage the inclined sides of their respective apertures 11 and 12 so that the joint is very rigid and 5 secure although readily detachable when desired.

In the drawing I have shown a pair of lugs and apertures, one above the other on 10 each plate but it is obvious that the number and position of each lug and aperture may be changed to conform with any desired requirements.

If desired, the plate 13 may be omitted 15 and other means of supporting the bed spring may be provided. The plate 13 may be also altered in shape or placed so that the same extends in any desired way from the corner plate.

From the foregoing it is obvious that my 20 invention is not to be restricted to the embodiment herein shown but is broad enough to cover all structures coming within the scope of the annexed claims.

Having described my invention, what I 25 claim is:—

1. A device of the class described comprising two members of an article, a plate having sides, oppositely disposed wedge shaped projections on the members, said 30 plate having complementary oppositely disposed wedge shaped openings in its sides which frictionally engage said projections to hold the members together.

2. A device of the class described comprising a side member and an end member, said members being arranged to be placed together at an angle to one another, a plate secured on each of said members, projections on said plates, the projections on one

of said plates comprising a plurality of upturned hooks, the projections on the other plate comprising a plurality of down turned hooks, a connecting plate having its sides angularly disposed, and provided with oppositely disposed apertures to engage the 45 oppositely disposed hooks.

3. A device of the class described comprising a pair of members arranged to be placed together at an angle to one another, projections on each of said members, the 50 projections on one of said members comprising a plurality of upturned wedge shaped hooks, the projections on the other plate comprising a plurality of down turned wedge shaped hooks, a connecting plate 55 having its sides provided with oppositely disposed apertures through which the hooks on the members project and are movable therein.

4. A device of the class described comprising a pair of members arranged to be placed at an angle to one another, projections on each of said members, the projections on one of said members comprising a plurality of upturned wedge shaped hooks, 60 the projections on the other plate comprising a plurality of down turned wedge shaped hooks, a connecting plate having a pair of vertical angularly disposed sides provided with oppositely disposed apertures 70 through which the hooks on the members project and are movable and a supporting plate formed on the lower end of the vertical sides.

Signed at the city of New York, county 75 of New York and State of New York this 15th day of June, 1917.

ADOLPH BALLENBERG.
